UNITED STATES PATENT OFFICE.

JOHN B. FLUETTE, OF LEWISTON, MAINE.

NUT-LOCK.

SPECIFICATION forming part of Letters Patent No. 341,469, dated May 11, 1886.

Application filed March 6, 1886. Serial No. 194,226. (No model.)

To all whom it may concern:

Be it known that I, JOHN B. FLUETTE, of Lewiston, in the county of Androscoggin and State of Maine, have invented certain new and useful Improvements in Nut-Locks; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a side sectional elevation of one side of my improved locking-nut. Fig. 2 is a side sectional elevation of another side. Fig. 3 is a top plan. Fig. 4 is a side view of a bolt with its nut and my locking-nut thereon. Fig. 5 is a sectional view of my nut with the spring-catch removed. Fig. 6 is a top plan of the slotted nut.

Same letters show like parts.

The object of my invention is to produce a locking-nut to keep in place the common nut, such as is screwed onto a threaded bolt to hold different portions of any kinds of structures together to which the bolt may be applied.

My invention shows an ordinary nut with the channel *a* cut therein, the part *b* being at 30 right angles to the part *c*, as seen in Fig. 3. Into this channel I fit the spring-catch *d*, pivoted at *e*, and having the thumb-piece *f*. The spring-catch has also the portion *g* extending down through the thickness of the lock-nut, 35 and projecting through the hole *h* in and through the nut, as illustrated.

i is a helical spring to keep the lower end of the portion *g* projected through the nut, except when, by pressure upon the thumb-piece 40 *f*, it is drawn up into the hole in the nut.

The nut *j* is provided on its face of intended contact with the locking-nut with slots *k*, to receive the lower protruding end of the part of the spring-catch *d*. The bolt *l* is passed through the parts of a structure desired to be held together by it. The locking-nut is then slipped onto the bolt *l* and pressed firmly or closely against the face of the object to be bolted. The nut *j* is then screwed onto the bolt and until it presses up closely against the face of the locking-nut. The lower portion *g*, of the spring-catch is drawn into the hole in the locking-nut by pressing on the thumb-piece, so as to allow the nut *j* to revolve until it is screwed closely up to the locking-nut. 55 The pressure is then removed from the thumb-piece, and the lower end, *g*, of the spring-catch allowed to slip into one of the slots *k*, and thus lock the nut *j* and prevent it from turning on the thread of the bolt. The nut *j* is thus securely locked in position.

What I claim as my invention, and desire to secure by Letters Patent of the United States, is—

In combination with a threaded bolt and the nut *j*, having the slots *k*, as set forth, the lock-nut with its channel *a*, with parts *b* and *c*, and hole *h*, into which works, as described, the spring-catch *d* *g*, having thumb-piece *f* and pivot *e*, and helical spring *i*, all as herein described. 70

In testimony that I claim the foregoing as my own I affix my signature in presence of two witnesses.

JOHN B. FLUETTE.
